Des. 231,310

Patented Apr. 16, 1974

231,310

RING FOR HOLDING A PAIR OF SOCKS OR THE LIKE

James F. Burgher, 3528 NE. 97th,
Seattle, Wash. 98115

Filed June 5, 1972, Ser. No. 260,063

Term of patent 3½ years

Int. Cl. D7—05

U.S. Cl. D7—198

Fig. 1.

Fig. 2.

Fig. 3.

FIG. 1 is a top perspective view of a ring for holding a pair of socks or the like showing my new design.

FIG. 2 is a plan view thereof.

FIG. 3 is an elevational view thereof.

I claim:

The ornamental design for a ring for holding a pair of socks or the like, substantially as shown and described.
